UNITED STATES PATENT OFFICE.

PATRICK M. REILLY, OF SOUTH CHICAGO, ILLINOIS.

CORE BARREL.

Application filed November 22, 1922. Serial No. 602,517.

To all whom it may concern:

Be it known that I, PATRICK M. REILLY, a citizen of the United States, residing at South Chicago, in the county of Cook and 5 State of Illinois, have invented certain new and useful Improvements in Core Barrels, of which the following is a specification.

My invention relates to core barrels and has particular reference to a device of this 10 character which is not affected by the heat absorbed from the metal when the ingot molds are being produced and which will operate properly with a minimum of expense for repair parts in service, and consists of only three primary parts, namely a 15 main stave, a base upon which said stave is mounted, and a secondary stave loosely secured to the said main stave.

A further object of my invention is the 20 production of a core barrel composed of few and simple parts which are easily molded in themselves and which when fitted together to form a unit make a complete and strong structure without likelihood of getting out 25 of order and failing to perform its proper function.

Another and further object of my invention is the provision of a core barrel which is securely held in position upon the base 30 for the ingot mold for the pouring operation and which is readily removable therefrom when the core barrel is removed from the mold.

As will be understood by those skilled 35 in the art, the production of steel ingots is accomplished by casting the fluid metal in molds. The molds in which this metal is cast are themselves formed of cast metal, are very heavy, and are usually about six 40 feet in height and are rectangular in cross section. The practice in the production of these ingot molds is to employ a core of proper dimension, coating the core with sand and then drying the sand until the sand coating 45 is rigid and hard, then surrounding the core with a flask and pouring the molten metal in the opening between the flask and the core. When the fluid metal has set, then the core is removed and it is to this par-

ticular feature that my invention is particularly directed.

As will be understood, the metal in cooling contracts and binds itself tightly upon the core and it is usually necessary to use a great deal of force in stripping the ingot 55 mold from the core and it has been the practice to form these cores of a number of staves built up around a tapered core member and slidably mounted thereon so that when the staves are raised, the core barrel 60 contracts thus allowing for its easy removal from the ingot mold. The use of a great number of parts of which these core barrels are composed and the absorption of the heat from the molten metal poured therearound 65 and the consequent warping of these parts, has made it difficult to secure the ingot mold in position on the stem during the pouring operation. My invention has to do with the 70 overcoming of these difficulties and the producing of a core barrel which will perform its function properly at all times with a minimum of repair.

These and other objects of my invention will be more fully and better understood 75 by reference to the accompanying drawings and in which—

Figure 1 is a side elevational view of my improved core barrel;

Figure 2 is a vertical sectional view taken 80 on a line at right angles to the core barrel as shown in Figure 1;

Figure 3 is a vertical sectional view of the main stave detached from the base;

Figure 4 is a vertical sectional view of 85 the loose stave;

Figure 5 is a sectional view through the bottom of the ingot mold and showing the base; and

Figure 6 is a top view of the mold showing 90 the separating wedges in position between the two mold sections.

Referring now specifically to the drawings, a base or cope 10 is shown upon which the main stave 11 of the core barrel is mounted, 95 the said stave having an extensible base portion 12 at the bottom thereof of the full size of the core barrel and upon which a sec-

2
ond stave 13 rests and which extends in vertical relation with the main stave or section 11 of the core barrel and is slightly movable relatively thereto. The base of the stave 11 has a hole 14 extending therethrough adapted to register with the hole 15 extending through the base 10 and through which a pin 16 passes, the said pin having a key 17 inserted through the lower end thereof 5 which serves to hold the main pin 16 in position and holds the section 13 of the core barrel firmly onto the base 10. A pair of bolts 18 and 19 are provided which prevent the main stave 13 from rotating about the pin 14 and a pair of openings 20, 20 are provided in register with a second pair of openings 21, 21 in the base through which the gas escapes at the bottom of the mold, or new sand or other particles inside the core barrel can drop onto the base. The loose stave 13 is positioned upon the projection 12 and is secured to the main stave 11 by means of a horizontally extending bolt 22 at the lower portion of the barrel and a second bolt 23 at the upper portion thereof. 10

The loose stave 13 has an inwardly projecting portion 24 which extends into a recess 25 on the main stave 11, so that it is held in proper position upon the main stave 13 and prevented from rotating about the said stave 11. The main stave has an upwardly extending post 26 secured thereto with a transversely extending hole 27 therein within which a clevis or a pin can be placed for purposes of securing a hoisting mechanism thereto when it is desired to remove the core barrel from an ingot mold. The post 26 has a vertically extending opening 28 therethrough which is in register 15 with a hole 29 in the projecting lug 24 so as to allow the gases to escape during the pouring of the metal forming the ingot mold. For purposes of spreading the mold a pair of wedges 30 and 31 are inserted between the sections 11 and 13 at their upper edges, this limit of movement being controlled by the bolt 23 in order to provide the proper formation of the proper sized mold and after the metal has solidified, the wedges 30 and 31 are removed allowing the core barrel 20 to collapse so that the same may be removed from the ingot mold.

In operation of the device, the section 13 is secured to the base 10 and coated with sand which is dried and the mold built up around it. A metal is thereupon poured around the core barrel and after becoming solid the wedges 30 and 31 are removed allowing the sections of the core barrel to collapse at the upper portion, the bolt 23 being inserted in recesses 32 and 33 formed in the sides of the two members 11 and 13 respectively so that the end of the bolt does not come in contact with the hardened metal. The two sections thereupon collapse 25

until their marginal edges meet and a hoisting device is secured to the post 26, the cotter pin 17 is removed from the base and the core barrel lifted out of the ingot mold. The loosening of the core barrel at the top 70 allows only a slight amount of surface of the core barrel at the base to remain in contact with the metal so that the core barrel is easily removed from the mold.

While I have described more or less precisely the details of construction, I do not wish to be understood as limiting myself thereto, as I contemplate changes in form and the proportion of parts and the substitution of equivalents as circumstances may 75 suggest or render expedient without departing from the spirit or scope of my invention.

I claim:

1. In combination, a core barrel comprising a main stave having an integrally formed enlarged projecting bottom portion, a second stave seated upon the projecting bottom portion of the main stave, bolts extending through each of said staves limiting 80 their outward movement and wedges adapted to be inserted between the said staves whereby the staves are forced outward from each other to the limit fixed by the said bolts. 85

2. In combination, a core barrel comprising a main stave having an integrally formed enlarged base portion, a second stave seated upon said projecting base portion, transversely extending bolts securing the said staves together and wedge members adapted to be inserted between the said staves for forcing them apart to the limit fixed by the said bolts. 100

3. In combination, a core barrel comprising a main stave having an integrally formed enlarged base portion, a second stave seated upon said projecting base portion of the first mentioned stave, transversely extending bolts securing the said staves together 105 and wedge members adapted to be inserted between the said staves for forcing them apart to the limit fixed by the said bolts.

4. In combination, a core barrel comprising a main stave having an integrally formed enlarged projecting bottom portion, a second stave adapted to be seated upon said projecting bottom portion, transversely extending bolts securing the said staves together, wedge members adapted to be inserted between said staves for forcing them apart, the said second stave having a projection at its upper part adapted to cooperate with a recess formed in said first mentioned stave, whereby the relative vertical movement of the second stave is limited. 115

5. In combination, a core barrel comprising a main stave having an integrally formed enlarged projecting bottom portion, a second stave seated upon the projecting 120

bottom portion of the first mentioned stave, transversely extending bolts securing the said staves together, wedge members adapted to be inserted between said staves for forcing them apart, the said second stave having a projection at its upper part adapted to cooperate with a recess formed in said first mentioned stave, whereby the relative vertical movement of the second stave is limited, a base, a pin extending through said base portion and the enlarged bottom portion of the said main stave, and a removable pin inserted through said holding pin.

Signed at South Chicago, Illinois, this 16th day of November, 1922.

PATRICK M. REILLY.
